UNITED STATES PATENT OFFICE.

OSCAR JAMES SEE, OF PEORIA, ILLINOIS.

OIL BURNER.

Application filed January 17, 1927. Serial No. 161,646.

This invention has particular relation to burners embodying among other characteristics a manifold for introducing air with the fuel to produce a highly and quickly inflammable mixture.

Another object of the invention contemplates a weight operated draft regulator adapted to check the ingress and egress of draft by means of which the heat radiated from the burner will remain constant.

A further object of the invention comprehends a drain pipe carried by the burner pan adapted for filling a receptacle carried by a trip valve for the supply pipe whereby fuel will be cut off when overflow takes place.

An additional improvement embodies a burner ring adapted to reflect flames and heat from the burner to produce a more thorough and quickly inflammable mixture. Said action of reflected heat causes air drawn through the manifold to be heated before mixing with the fuel whereby a highly expansive mixture is produced.

With the foregoing and other objects in view, the invention further consists of the following novel features and details of construction, to be hereinafter more fully described, illustrated in the accompanying drawings, and pointed out in the appended claim.

In the drawings:—

Figure 1 is an elevation of the invention as applied for active use.

Figure 2 is an elevation of a flue pipe with parts broken away to illustrate the draft regulator.

Figure 3 is a transverse section taken through the burner apparatus.

Figure 4 is a sectional view of the relative association of a burner and manifold.

Figure 5 is a sectional view taken on line 5—5 of Figure 4.

Figure 6 is a sectional view of a modified form of the burner.

Figure 7 is a sectional view taken on the line 7—7 of Figure 6.

Referring to the drawings, wherein like characters of reference denote corresponding parts the reference character 10 indicates a conventional form of heating plant provided with a draft pipe 11 including a damper 12.

In carrying out the invention I provide an auxiliary section 13 depending from the flue pipe and provided with a collar 14 carried by a plate 15 within the open end thereof to

provide a restricted entrance through the section 13. An arm 16 pivotally mounted upon the plate 15 is provided with a disk member 17 upon one end disposed within the section 13 and adapted to be seated upon the collar 14. The opposed end of the arm is threaded for engagement with a weight 18 balancing the arm to check undue draft ingress and egress through the flue pipe 11. The purpose of such mechanism will be more specifically pointed out with reference to subsequent description of the invention.

A ring 19 is suitably anchored upon a platform 20 disposed at an appropriate height within the fire-box of the furnace 10. Said platform is provided with legs 21 depending therefrom and engageable with the ash-pit to support and materially strengthen the platform. An air manifold 22 extended within the fire-box is extended upwardly within a flange portion 23 carried by the platform 19. An elbow 24 is carried by said manifold. An auxiliary section 25 has the opposed ends thereof extended within flange portions 23 of the platform 19 and communicating with the respective ends of the manifold and elbow. The intermediate portion in the length of the auxiliary section 25 of the manifold is provided with an opening surrounded by outwardly flared side walls 26. A drain pan 27 is disposed upon the upper side of the manifold 22 and between the inner extremity thereof and the elbow 24. A supply pipe 28 extended within the fire-box is provided with an offset discharge end 29 extended upwardly through the bottom and centrally of the drain pan 27 and threaded within the bore of a frusto-conical burner 30. Said burner may be either provided with discharge ports 31 extending in diametrically opposite directions from the bore thereof or slotted portions 32 disposed in staggered relation thereon. A burner pan 33 is carried upon the base of the burner. An annular burner ring 34 is also seated within the flange portions 23 of the platform 19 in spaced relation to the inner side walls of the furnace 10. A needle valve 35 is carried by the supply pipe 28 to check the feed of the fuel to the burner. A drain pipe 36 connected with the drain pan 27 has the outer discharge end thereof disposed directly above a receptacle 37 carried by a trip valve 38 upon the supply pipe 28 in order that excess fuel unburned will automatically check the flow of the fuel.

Thus a material saving in the consumption of fuel will be had in so far as the mechanism will be automatically shut off when such condition occurs.

5 In the operation of the invention oil collecting within the burner pan 33 is ignited and burned for an appreciable length of time to heat the burner 30 until the discharged contents thereof are ignited. The 10 flames emitted therefrom will be directed against and within the manifold section 25. Such action in conjunction with the draft regulator, as mentioned in foregoing, will cause a sufficient quantity of air to be drawn 15 through the manifold section. The inrushing air, being preheated, will vaporize the fuel whereby greater heat is produced. The burner ring 34 is adapted to deflect the flames and reflect the heat toward the manifold section 25 whereby better combustion 20 will be produced.

Further preheating of the air is done in the manifold 22 and in its expanded state considerable friction is produced to obviate 25 violent flame pulsations. The draft regulator is adapted to overcome the usual difficulty of burners and fire therefor from being blown out and considerable fuel wasted by the ingress and egress of draft. The 30 great economy in oil burning lies in the proper regulation of the draft, particularly when air eddies or violent gusts of wind out-

side would tend to blow out the fire. With the burner ring 34 to retain the heat and the flame a constant economical flame is 35 produced which is retained constant due to the mixing of the preheated air with the fuel.

The invention is susceptible of various changes in its form, proportions, and minor 40 details of construction, and the right is herein reserved to make such changes as properly fall within the scope of the appended claim.

Having thus described the invention, what 45 I claim is:—

An oil burner apparatus comprising a platform, a manifold comprising upper and lower sections, the lower section being supported upon the platform, one end of the 50 section being offset, an elbow carried by the lower section being projected in parallelism with the end thereof, the upper section being adapted for connection with the end of the lowermost section and the elbow, the upper section being provided with an opening 55 therein, a burner disposed in juxtaposition to said opening, and a burner ring carried by the platform and surrounding the manifold adapted to reflect heat from the burner 60 upon the manifold to cause the heating of the air.

In testimony whereof I affix my signature.
OSCAR JAMES SEE.
